Primary Examiner — Eric L Goodman*Assistant Examiner* — Sarah L Smith(74) *Attorney, Agent, or Firm* — Kilpatrick Townsend & Stockton LLP(57) **CLAIM**

The ornamental design for a light fixture, as shown and described.

DESCRIPTION

FIG. 1 is a top perspective view of a light fixture.

FIG. 2 is a bottom perspective view taken from a bottom, right side thereof;

FIG. 3 is a left side elevation view thereof;

FIG. 4 is a right side elevation view thereof;

FIG. 5 is a front side elevation view thereof;

FIG. 6 is a rear side elevation view thereof;

FIG. 7 is a bottom plan view thereof; and,

FIG. 8 is a top plan view thereof.

The light fixture is shown with a symbolic break in its length. The appearance of any portion of the article between the break lines forms no part of the claimed design.

1 Claim, 6 Drawing Sheets(56)
